SIMULATED COIN

Stanley F. Dann, Oakland, Calif., assignor to World
Commerce, Vacaville, Calif.

Continuation-in-part of design application Ser. No.
25,752, Oct. 30, 1970. This application June 21,
1971, Ser. No. 155,387

Term of patent 14 years

Int. Cl. D11—03

U.S. Cl. D29—11 F

2—
Fig-1

Fig-2

Fig-3

FIG. 1 is a top plan view of a simulated coin showing my new design;

FIG. 2 is a sectional view taken along line 2—2 of FIG. 1; and

FIG. 3 is a bottom plan view.

This application is a continuation-in-part of copending application Ser. No. D. 25,752, filed Oct. 30, 1970, and now abandoned.

I claim:

The ornamental design for a simulated coin, substantially as shown and described.
